(57) CLAIM

The ornamental design for a footwear outsole as shown and described.

DESCRIPTION

FIG. 1 is a front perspective view of a footwear outsole showing my new design;

FIG. 2 is a bottom view thereof;

FIG. 3 is a side view thereof;

FIG. 4 is an opposite side view thereof;

FIG. 5 is a front view thereof;

FIG. 6 is a rear view thereof; and,

FIG. 7 is a top view thereof.

The even dashed broken lines represent portions of the footwear that form no part of the claimed design.

1 Claim, 6 Drawing Sheets
